UNITED STATES PATENT OFFICE.

ALBERT B. MEYER, OF CHICAGO, ILLINOIS.

ASH-RECEPTACLE FOR FURNACES.

1,137,158.

Specification of Letters Patent. Patented Apr. 27, 1915.

Application filed February 13, 1915. Serial No. 8,037.

To all whom it may concern:

Be it known that I, ALBERT B. MEYER, a citizen of the United States, residing at Chicago, in the county of Cook and State 5 of Illinois, have invented certain new and useful Improvements in Ash-Receiptacles for Furnaces, of which the following is a specification.

This invention relates to devices for removing ashes from the ash pit of furnaces, its object being to effect removal of the ashes without stirring up dust and dirt.

The herein stated object is attained by means of a novel combination and arrangement of parts to be hereinafter described and claimed reference being had to the accompanying drawing, in which—

Figure 1 is a vertical section of a fragment of the furnace showing the application of the invention, and Fig. 2 is an enlarged cross-section on the line 2—2 of Fig. 1.

Referring specifically to the drawing, 5 denotes a furnace provided with the usual grate 6 beneath which is an ash pit 7. In the floor or other foundation on which the furnace is set is a pit 8, the same being located directly beneath the ash pit 7 to form a continuation of the latter. The pit has a 10 passageway 8^a which projects a short distance beyond the back of the furnace base and leads to a deeper cavity or second pit 9 opening through the floor or foundation and designed to hold a receptacle which receives 15 the ashes. The cavity 9 has a metal lining 10 comprising a box-shaped casting dimensioned to fit snugly therein. The casting is open at the top and has a spout 11 on one side which extends into the passageway 8^a and connects the pit 8 with the second pit 9.

A cover plate 12 is provided for closing the open top of the pit lining 10. Adjacent to the edge of the cover plate, the same has a depending bead 13 which seats in a channel 14 in the top rim of the lining, said rim being widened to obtain enough metal for the channel. By providing the cover plate with this bottom bead seating in the channel of the lining rim, a dust proof closure 20 for the lining is provided. The cover plate is hinged to the lining rim as indicated at 15.

At 16 is denoted a receptacle designed to be lowered into the cavity 9, within the lining 10, to receive the ashes from the furnace 5. This receptacle has an opening 17

in one side to register with the spout 11, and it is also provided with a bail 18 to facilitate handling. The inner or outlet end of the spout 11 projects for a slight distance into the lining 10 as indicated at 19, 60 and the receptacle 16 is so dimensioned that it has sufficient side play in the latter to permit the projection 19 to enter the opening 17. The bottom of the lining has a slant toward the side of the cavity 9 on which is the projection 19 so that the receptacle will slide in this direction to receive the said projection 19.

In use, the receptacle 16 being in place, the ashes which have dropped into the pit 8 are 70 pushed by means of a shovel or other device to the spout 11 and they pass through the latter into the receptacle. The shovel can be inserted through the ash pit door 20 of the furnace 5. During this operation the 75 cover plate 12 will be left seated, thus forming a closure for the receptacle, and preventing the escape of dust. After the dust has settled in the receptacle, the latter will be removed after swinging the cover plate 80 open. Thus it will be seen that the ashes can be removed without raising any dust.

I claim:

1. The combination with a furnace, of an ash pit beneath the grate thereof, said pit 85 having a passageway projecting beyond the furnace base and having therein a cavity, a lining in said cavity, said lining having a side spout extending into the passageway, a receptacle removably mounted in the cavity, 90 within the lining, said receptacle having a side opening registering with the outlet end of the spout, and a closure for the cavity.

2. The combination with a furnace, of an ash pit beneath the grate thereof, said pit 95 having a passageway projecting beyond the furnace base and having therein a cavity, a lining in said cavity, said lining having a side spout extending into the passageway, 100 and the outlet end of the spout extending into the lining, a receptacle removably mounted in the cavity, within the lining, said receptacle having a side opening registering with the outlet end of the spout and receiving the said end of the spout, and a 105 closure for the cavity.

3. The combination with a furnace, of an ash pit beneath the grate thereof, said pit having a passageway projecting beyond the furnace base and having therein a cavity, a 110

lining in said cavity, said lining having a side spout extending into the passageway, and the outlet end of the spout extending into the lining, a receptacle removably mounted 5 in the cavity, within the lining, said receptacle having a side opening registering with the outlet end of the spout, and receiving said end of the spout, the bottom of the lining sloping toward the side of the lining

from which the spout extends, and a closure 10 for the cavity.

In testimony whereof I affix my signature in presence of two witnesses.

ALBERT B. MEYER.
